ELECTRIC HEATER AND METHOD OF
MAKING THE SAME

Allan P. Charbonneau, Wauwatosa, Wis., assignor
to Cutler-Hammer, Inc., Milwaukee, Wis., a corporation of Delaware

Application July 23, 1951, Serial No. 238,160

6 Claims. (Cl. 201—67)

1

This invention relates to improvements in electric heaters and methods of making the same; and the invention relates more particularly to sheathed electric heaters of the strip type.

A primary object of the invention is to generally improve the structural and operative characteristics of electric heaters of the aforementioned type.

Another object is to facilitate production and assembly of the heater parts.

Another and more specific object is to provide an improved electric heater employing a resistor in the form of an elongated helix whereby a long and efficient resistor path is insured.

Another object is to provide novel means for properly anchoring the resistor during and after filling of the sheath with a granular non-cementitious insulating material.

Another object of the invention is to provide an improved method of making electric heaters of the aforementioned type.

Other objects and advantages of the invention will hereinafter appear.

In the drawings accompanying this application, I have shown for purposes of illustration several forms which my invention may assume, and in these drawings

Figure 1 is a fragmentary bottom plan view with the base portion of the sheath removed and showing an arrangement with terminals at either end;

Fig. 2 is a fragmentary side elevational view of a partially assembled heater positioned vertically to facilitate the filling operation;

Fig. 3 is a fragmentary side elevational view of a completed embodiment of the invention having terminals at each end;

Fig. 4 is a fragmentary top plan view of the strip heater illustrated in Fig. 3;

Fig. 5 is a fragmentary side elevational view of the embodiment having both terminals at one end of the heater and having part of the sheath broken away, and

Fig. 6 is a fragmentary top plan view of the strip heater illustrated in Fig. 5.

Referring to Figs. 1 through 4, the numeral 10^a designates one of the punched and stamped sheet metal parts of a sheath or casing, said part being formed to provide a recess 10^b of substantially rectangular form both in transverse and longitudinal cross section and the same having relatively narrow longitudinal flanges 10^c and relatively large end flanges 10^d. Recess 10^b is provided in its bottom wall adjacent to each end thereof with relatively large openings 10^e which are preferably of circular contour. Located 55

2

within said ends of recess 10^b are plates 11 of insulating material such as mica. Plates 11 are provided with openings 11^a just sufficiently large to accommodate the threaded shank 12 of a bolt 5 having a flat head 12^a. Interposed between said plate 11 and bolt head 12^a are an insulating member 13 and a sheet metal part 14. Said sheet metal part 14 is provided with an aperture 14^a to slidably accommodate the shank 12 of the above mentioned bolt and is fastened to the shank side of the flat head 12^a as by means of welding. Said sheet metal part 14 is also constructed with a lip or upturned end portion 14^b as shown in Fig. 2. The insulating member 13 is also constructed with an aperture 13^a to slidably receive the shank 12 of said bolt. Said insulating member 13 is assembled in juxtaposition with plate 11 and is constructed with an aperture 13^b to receive the above-mentioned lip 14^b of the sheet metal member 14. The plate 11 and insulating member 13 are of such dimensions as to fit against the bottom wall of recess 10^b and to bear slightly against the side walls of said recess to prohibit any rotational displacement between either of 15 said members and the casing part 10^a. It is apparent that the engagement between the lip 14^b and the aperture 13^b of said insulating member 13 prevents rotational movement of said sheet metal part 14 and said bolt with respect to the casing part 10^a.

30 Rigidly attached to the flat head 12^a of the bolt as by spot-welding is a punched and stamped sheet metal bracket 15, said bracket being of substantially U-shape and having end portions 15^a and 15^b thereof offset from the flat head 12^a of the bolt. The ends 15^a and 15^b of bracket 15 are reflexed or hook-shaped, as best illustrated in Figs. 1 and 2.

Attached to the bracket 15 by means of the hook-shaped end portion 15^b is an insulating ring 16. Said insulating ring 16 is constructed of mica or any well known insulating material and although it may be constructed to any desired shape the preferred construction is as shown in Fig. 1. Also attached to said insulating ring 16 40 is a sheet metal supporting member 17 so positioned on said ring 16 as to prevent electrical conductivity between the bracket 15 and said member 17. Said supporting member 17 is constructed with a reflexed portion and engages the ring 16 in the same fashion as bracket 15 engages said ring 16. Supporting member 17 is also constructed with a curved arm 17^a to receive a helical resistor 23 when said resistor 23 is subsequently reflexed between the terminals.

45 A mica insulating washer is strung upon the

shank 12 of the bolt and fits within the opening 10^c in the bottom wall of recess 10^b at one end of the latter. A relatively larger mica washer 19 is then strung upon shank 12, then a metal washer 20 and a nut 21 which is adapted to clamp all the parts of the terminal to the sheath part 10^a. A second nut 22 threadably engages shank 12 of the bolt so as to provide a means for clamping a circuit wire (not shown) between the nuts 21 and 22. The terminals at each end of the 10 casing part 10^a are of identical form and are attached in a like manner.

The heating element 23 is constructed of a wire preferably composed of a known alloy of nickel and chromium which is adaptable for 15 use as a heater resistor and is formed into an elongated helix of relatively small diameter. A coil of relatively small diameter is used to overcome the excessive sagging inherent in large diameter helical resistors.

The resistor 23 is initially assembled within the recess 10^b by rigidly attaching one of the free ends of said resistor to one of the hooked ends 15^a of a bracket 15. This is accomplished by inserting the free end between the arms of said 20 hooked end and then pressing said arms together as by means of a pliers to provide a good mechanical and electrical connection between the same and the end of the wire. Resistor 23 thus anchored is then extended toward the second terminal and reflexed about the supporting member 17 of said second terminal. This step is then repeated so as to bring said resistor 23 back toward the first terminal and reflex it about the supporting member 17 attached to said first 25 terminal member. After the second reflex operation the resistor is extended toward and fastened to the arm 15^a of the second terminal in the same fashion as the resistor 23 was initially anchored to the first terminal as above described. It is an essential feature of this invention that the resistor 23 be kept reasonably taut so as to prevent excessive sagging thereof throughout 30 subsequent operations.

With the terminal members and the resistor 23 thus positioned within and attached to the sheath part 10^a, a cover plate 24 is attached to the latter. Said cover plate 24 has one of its ends 24^a bent over one of the end flanges 10^b of sheath part 10^a and its longitudinal edges 24^b bent over a major portion of the length of flanges 10^c to provide a seam connection between the sheath parts. As shown in Fig. 2, however, a portion of the seam connection is left incomplete and the unattached end of cover 24 is bent or curved outwardly to provide an opening at that end of the sheath. The sheath is then positioned vertically upon a suitable support. Thereupon the granular non-cementitious insulating material is introduced by gravity into the sheath through the open upper end thereof as by means of a funnel 25. The support will preferably be vibrated vertically to a slight degree to insure complete filling of the sheath.

While various granular non-cementitious insulating materials, as, for instance, quartz sand, have been found practical, I prefer to employ magnesium oxide because of the good heat conducting and dielectric properties thereof when treated in the manner herein contemplated by me. When the sheath has been filled the remainder of the edge portions 24^b of the cover plate 24 are bent into overlapping relation to flanges 10^c, as shown in Figs. 3 and 4, to completely close the sheath. Thereafter the heater

is placed in a pressure die and subjected to a relatively high pressure between points indicated at 26 and 27. This portion of the sheath is thus reduced in thickness and the granular insulating fill is crushed and highly compacted whereby the resistor helix is positively fixed in spaced relation to the inner walls of the sheath, whereas the compaction of insulation affords a good path for conduction of heat from the resistor. At any stage following the overlapping of end portions 24^a of cover plate 24 the completely assembled heater is provided at opposite ends with suitable openings 28 and 29 to provide for attachment of the heater to a support.

Figs. 5 and 6 depict an embodiment of the invention wherein both terminals are located at the same end of the sheath. At the end of the sheath not having said terminals, the bottom wall of said sheath part 10^a has attached thereto as by means of welding a bracket 15 above described. To insure centrally locating the resistor 31 within the sheath it is necessary to provide said bottom wall of sheath part 10^a with a protuberance 30 to which said bracket 15 is attached as described. Each of the ends of bracket 15 has attached thereto a ring 16 and a sheet metal supporting member 17. As shown in Fig. 6, the helical resistor 31 in this embodiment is of substantially the same diameter as that of resistor 23 of the first described embodiment, and like said first described embodiment is reflexed between the brackets 15 (Fig. 6).

While I have described in detail herein the method of and means for producing an electrical heater of the strip type it is to be understood that certain features of the invention have utility as applied to electric heaters of other types. Also it will be apparent that various changes and modifications can be made without departing from the scope of the invention.

I claim:

1. A resistor supporting and wiring terminal assembly for electric heaters of the sheath type, comprising a bolt having a flat head to be positioned within the sheath of the heater, a stamped sheet metal member welded to said head, said member having portions offset from said head, one of said portions constructed with clamping means to securely engage the end of a wire resistor, means attached to said other offset portion and including a flat mica insulating member for holding a reflexed portion of the wire resistor in spaced relation within said sheath.

2. A resistor supporting and wiring terminal assembly for electric heaters of the sheath type, comprising a bolt having a flat head to be positioned within the sheath of the heater, means attached to said bolt for anchoring said bolt against rotational displacement relative to said sheath, a stamped sheet metal member welded to said flat head, said member having portions offset from said head, the end of one of said portions being hook-shaped to clampingly engage the end of a wire resistor, the other of said offset portions having means attached thereto and insulated therefrom to receive a reflexed portion of the resistor to maintain said reflexed portion in a predetermined position within said sheath.

3. A resistor supporting and wiring terminal assembly for electric heaters of the sheath type, comprising a bolt having a flat head to be positioned within the sheath of the heater, means associated with said bolt for anchoring said bolt against rotational displacement relative to said

sheath, a stamped sheet metal member welded to said bolt head, said member having hook-shaped end portions offset from said head, one of said end portions clampingly engaging the end of a wire resistor, the other of said offset portions having an insulating member attached thereto, and means cooperating with said insulating member to position a reflexed portion of the resistor within said sheath.

4. For a sheathed electric heater of the strip type having a reflexed resistor, a substantially flat resistor supporting assembly comprising a stamped sheet metal member positioned within the sheath and formed with an offset portion, a flat mica insulating member attached to said offset portion and a supporting member attached to said insulating member for supporting a reflex of the resistor in insulated relation to said sheath and to said sheath metal member.

5. For a sheathed electric heater of the strip type having a reflexed resistor, the number of reflexes depending upon the heater size and arrangement desired, a resistor supporting and wiring terminal assembly, comprising a bolt having a flat head to be positioned within the sheath of the heater, a stamped sheet metal member welded to said head and formed with a plurality of offset portions, means including an insulating member and a supporting member attached to said insulating member, one of said offset portions being adapted to clampingly retain an end of the wire resistor and the other

10

15

20

25

30

of said offset portions being adapted to retain said insulating member for supporting said reflexed resistor in insulated relation to said sheath and to said sheet metal member.

5. For a sheath type electric heater having a reflexed resistor, the number of reflexes depending upon the heater size and arrangement desired, a resistor supporting and wiring terminal assembly, comprising a bolt positioned partly within the sheath of the heater, a sheet metal member attached to said bolt within said sheath and formed with an offset portion, said offset portion being formed with a hook to clampingly engage the end of the wire resistor and said portion being formed with a second hook to engage an insulated supporting member to which is fastened one of the reflexes of said resistor to thereby position said reflex within said sheath.
